UNITED STATES PATENT OFFICE.

GEORGE M. BICKNELL, OF ST. LOUIS, MISSOURI.

CARBURETOR.

Application filed March 31, 1921. Serial No. 457,247.

My invention relates to improvements in carburetors and has for its primary object the construction of a carburetor with few moving parts and capable of supplying a large volume of fuel when required without materially enlarging the same.

In this chamber is contained the float 8 which operates the needle valve 9. This is for the purpose of maintaining a pre-determined level of fuel within the chamber 7. Located in the chamber 7 is a needle valve 10 which controls the admission of fuel from

A further object is to construct a carburetor that will maintain a uniform quality of mixture throughout its throttling range and make due provision for a proper supply of fuel for pickup or acceleration under any condition of throttle opening either rapid or gradual.

10

In which controls the admission of fuel from chamber 7 to the passage way 11. This passage way terminates in the well 12. The housing is also provided with the air inlet 65 13 and the mixing chamber 14.

In the lower portion of the mixing chamber 14 is located a choke or venturi 15. Located in the upper portion of chamber 14

A further object is to construct a carburetor having an adjustable idling tube that will properly idle an engine with the throttle set for a certain speed and continue to deliver a uniform mixture therefrom throughout the initial stages of throttle opening until sufficient suction has been applied to the main fuel nozzle to insure a proper flow of fuel therefrom.

The tendency at the present time in the construction of internal combustion engines is to reduce the piston displacement and to increase their power through greater engine speed which makes it necessary to use larger carburetors in proportion to the size of the engine and consequently, a larger choke or venturi. This choke must be of a sufficient size to supply the necessary volume of mixture for the greatest motor speed and to successfully use a carburetor of this construction, it has been found advantageous to increase the range of the low speed or idling device as much as possible, so that a relatively large volume of air is passing through the choke at the time the main fuel nozzle takes up the load and supplies the fuel for the mixture.

In the drawings.

Fig. 1 is a side elevation of my improved carburetor.

Fig. 2 an enlarged vertical longitudinal sectional view of the same.

Fig. 3 a fragmental vertical section of a portion of the carburetor and the adjustable idling device.

Fig. 4 an enlarged section taken on the line 4-4 of Fig. 2 and viewed in the direction of the arrow.

Fig. 5 an enlarged elevation of the fuel tubes in the main fuel nozzle.

In the construction of my device I provide a carburetor comprising a housing 6 which has integrally therewith a float chamber 7. Projecting upwardly from nut 36 is the main fuel nozzle 39. This nozzle projects up into the venturi 15. Secured to the underside of

nut 36 is a bridge 40 and projecting through this bridge are the fuel tubes 41, 42 and 43. Their upper ends extending into the nozzle 39. It will also be noted that the upper ends 5 of the tubes all terminate in the same plane, while their lower ends project to various distances below the bridge 40. Secured to the nozzle 39 is a cap 44 which is provided on one side with a rack 45 which meshes 10 with the pinion 46. This pinion has its shaft 47 projecting through the side of the carburetor casing and to this projecting shaft is secured a lever 38. This lever has its free end attached to a suitable controlling means 15 for swinging the lever which operates the cap 44 up and down, so as to increase or reduce the amount of air flowing through the choke. This is for the purpose of priming the engine when the same is started or when 20 it is desired to increase the flow of fuel through the main nozzle. The lower portion of the cap 44 is provided with openings 49 which admit air to the interior of the cap. This air passing downward through the 25 opening 37 and then into the tubes 41, 42 and 43 and is for the purpose of compensating for increased suction due to increased engine speed. The well and stand pipe are so arranged that the gasoline level will be 30 approximately even with the underside of the nut 36 when the device is not being operated. The operation of my device is as follows:

The pipe 21 is first positioned by means 35 of the adjusting screw so that the groove 26 and opening 29 will be slightly above the valve 17 when the same is partially opened. This will allow the openings 29 to communicate with the suction portion of the mixing 40 chamber 14 above the valve 17. After the carburetor has been assembled and attached to the engine, the pipe 21 is first positioned by means of the adjusting screw 25 so that the groove 26 and openings 29 will be 45 slightly above the valve 17 when the same is partially open. When in this position the openings 29 will communicate with the mixing chamber above the valve 17. When the valve 17 is in this position and 50 the engine cranked there is only a small opening by which air can pass around the valve 17 into the engine and the suction created thereby moving past the opening 22 in the sleeve 16 will draw air out of the upper portion of the auxiliary chamber 20. Any air which enters the carburetor 55 below the valve will not only pass around the valve but a portion thereof will also be drawn through the opening into the auxiliary chamber 20, and will also enter through the openings 30 and 31 and pass out through the openings 29. This air entering through the openings 30 and 31 and passing out through the openings 29 will cause a partial 60 vacuum to be formed in the idler tube

and raise fuel therein, which fuel will be discharged through the openings 29 and into the mixing chamber above the valve 17. The amount of fuel thus delivered is sufficient to keep the engine turning over or running 70 without load. At this point the throttle valve is almost entirely closed and the suction created in the auxiliary chamber 20 is supplied through the opening 22 which is adjacent the edge of the throttle valve when 75 in its idling position.

The needle valve 10 is then adjusted so as to permit sufficient fuel to flow from the float chamber 7 into the passage 11 and well 12, the flow of fuel being greater than that 80 demanded by the idler tube so that the fuel will raise in the well to a sufficient height to submerge the end of the tube 41. This fuel level however is controlled by the float 8, in other words, when the fuel in the well 12 85 reaches this level the float automatically closes off the supply line so that the carburetor will not become flooded. As the throttle valve is opened its edge adjacent the passage or opening 22 moves downward, 90 this decreases the space in which the air can flow into the auxiliary chamber 20 and enlarges its outlet and at the same time brings the opening 30 above the throttle valve 17. All of the flow of air into the idling jet is 95 now through the openings 31, while fuel is delivered through the openings 29 and 30. A still farther opening of the throttle valve permits the openings 31 to also deliver fuel. When this takes place the throttle valve is 100 sufficiently opened to permit air to pass straight upward past the passage 22. This passage of air has a siphoning action and draws the air from the auxiliary chamber 20 which is replaced by fuel through the openings 105 29, 30 and 31. While this siphoning action in the auxiliary chamber 20 is taking place, siphoning action also commences on the main jet 39, by reason of the passage of air through the venturi or choke 15, and as air is withdrawn from the main jet 39 a suction is created within the cap 44 due to the fact that air is exhausted from the well. Fresh air is admitted through the openings 110 49 which is permitted by means of the spider 36. The air rushing through the nozzle 39 creates a suction in the tubes 41, 42 and 43. These tubes as soon as suction is created 115 therein, commence to deliver fuel. At this period the engine is running at a higher speed and consuming more fuel than the needle valve 10 allows to pass. In other words, a mixture rich in fuel is being delivered to the engine. As soon as the lower portion of the pipe 41 is uncovered, any suction created therein delivers only air and permits only the pipes 42 and 43 to deliver fuel. This delivery of fuel by both of these pipes continues until the opening 50 is 120 uncovered by the fuel, after which a mixture 125 130

of air and fuel is delivered by the pipe 42, while the pipe 43 still continues to deliver its full fuel only and an increase in speed further lowers the fuel level until the lower 5 end of the pipe 42 is uncovered. At this period both pipes 41 and 42 deliver only air, or rather a small quantity, which is drawn therethrough by means of the suction created in the main nozzle 39. The pipe 43 10 is now the sole source of supply and continues lowering the fuel level until the opening 51 therein is uncovered, after which it also delivers a mixture of air and fuel. This delivery of fuel is sufficient to keep the engine running at high speed and in furnishing the proper mixture, in other words, the construction of the tubes and regulation of the valve 10 is such that a properly proportioned mixture for running the engine at high speed will be maintained. As soon as 15 the engine is throttled down so that the quantity of fuel necessary to maintain the speed of the engine is reduced the fuel level will rise in the well and the delivery of fuel to maintain this reduced speed be divided 20 between two pipes. A further slowing down of the engine will bring into action all three pipes, but the suction being decreased by the slowing down of the engine a proper amount 25 of mixture will still be delivered, so that an increased amount of fuel is available for acceleration and upon the entire throttling 30 down of the engine to its lowest or idling speed the fuel level in the well and float chamber will be restored so that the engine can be readily accelerated. In this way my carburetor supplies an extremely rich mixture, for sudden acceleration, which gradually leans down automatically as the engine speed increases. The richest mixture 35 being delivered only temporarily and not for a sufficiently long enough time to choke the engine with an over rich mixture. In other words with my carburetor, it is practically impossible to stall the engine due to 40 sudden acceleration flooding the cylinders which makes it extremely useful when an automobile driver is caught traveling slowly in a dangerous position, such as on railroad crossings, etc., and must depend upon sudden acceleration to get out of danger as there is 45 very little possibility of killing the engine due to sudden acceleration when my device is employed. Furthermore with the construction of my device, the leaving off of 50 the idler jet action and the bringing into action of the main nozzle overlap each other either on speeding up or slowing down so 55 that there is no sudden leaving off of one and bringing on action of the other, with the 60 consequent possibility of a dead spot in between, which might kill the engine and cause a serious accident. Heretofore it has necessitated extremely delicate adjustment and a relatively large carburetor to permit a 65 sudden increase in speed without choking the engine, for the reason that a small carburetor has a relatively small well and upon sudden acceleration a rich mixture was fed to the engine which continued until practically 70 all of the fuel in the well was exhausted. It was therefore necessary to make use of a large carburetor and one which was capable of supplying more fuel at all times than was really needed by the engine. A 75 carburetor of this kind necessitated the use of many adjusting screws which when handled by inexperienced persons led to constant trouble and complaints.

It is to be understood of course that in the 80 slowing down of the engine which brings into action all three pipes, that the suction created by the engine reduces the speed at which the air travels through the main nozzle and consequently although all three 85 pipes may be delivering fuel the amount of fuel drawn from the pipes will be just sufficient to furnish a lean mixture for that particular speed of engine.

It is furthermore to be noted that upon 90 sudden acceleration the mixture is leaned out automatically, the first suction or two tending the uncover the lower end of the pipe 41, so in other words, the engine is only supplied momentarily with an extremely rich 95 mixture. This mixture being approximately sufficient to charge each cylinder once, after which the mixture is partially leaned out, which leaning out process continues until only the pipe 43 is in action.

Having fully described my invention, what 100 I claim, is:

In a carburetor comprising a casing having a float chamber, a mixing chamber, and an auxiliary chamber, said auxiliary 105 chamber opening into the mixing chamber, a valve mounted in the mixing chamber, an adjustable idler tube provided with a plurality of discharge openings arranged circumferentially and longitudinally adjacent 110 its upper end extending into the auxiliary chamber, and means for supplying fuel to said idler tube.

In testimony whereof I have signed my name to this specification.

GEORGE M. BICKNELL.
